UNITED STATES PATENT OFFICE.

ALBERT G. WUEST, OF MONROE, MICHIGAN, ASSIGNOR TO THE WEIS MANUFACTURING COMPANY, OF MONROE, MICHIGAN, A CORPORATION OF MICHIGAN.

CARD-INDEX DEVICE

Application filed March 7, 1925. Serial No. 13,726.

This invention relates to card holders for visible card index devices, or for similar things, such as those involving flat trays or drawers in which are provided cards held 5 in holders which permit the cards to lie down flatwise upon each other, when the trays or drawers are inserted in a cabinet, but which permit the cards to be raised and folded back away from each other, when it 10 is desired to inspect the memoranda on any particular card.

Generally stated, the object of the invention is to provide novel and improved means for holding the cards in position, so that the cards can be easily manipulated to inspect the memoranda thereon, and whereby any card and its holder can be easily removed without the necessity of removing any of the other cards and their holders, and whereby additional cards and their holders can be inserted at any point in the tray or drawer without the necessity of removing any of the other cards already in use.

It is also an object to provide a very simple and inexpensive construction, so that the cost of manufacture may be materially reduced, in the commercial production of visible card index devices of this character.

It is also an object to provide certain details and features of construction and combinations tending to increase the general efficiency and the desirability of visible card index devices of this particular character.

35 To these and other useful ends, the invention consists in the matters hereinafter set forth and claimed, and shown in the accompanying drawings, in which,—

Fig. 1 is a perspective of a flat tray or drawer for any ordinary cabinet, the said tray or drawer being equipped with cards and card holders embodying the principles of the invention.

Fig. 2 is a transverse section, on a larger scale, on line 2-2 in Fig. 1.

Fig. 3 is a face view of one of the cards and removable card holders.

Fig. 4 is a perspective of one end por-

tion of one of the card holders, showing a fragment of the card held therein. 50

As thus illustrated, the invention comprises a tray or drawer 1 of any suitable known or approved character, but preferably provided inside thereof, and longitudinally thereof, with guides 2 to receive the ends of the card holders. 55

The card holders are preferably made of sheet metal, and are each in the form of a tube having tubular end portions 3 and a flattened intermediate or middle portion 4, in which latter the cards 5 are held. Each card holder has a slot 6 on one side thereof for the insertion of a card. Preferably, a card is inserted by inserting its corner in one end of the tube, and by then sliding the card along in the slot with the inner edge of the card bearing against the inside of the rear edge 7 of the middle flat portion of the sheet-metal holder. Each holder can have any suitable means for limiting this inserting movement of the card, as by providing an internal dent or hump 8 in the sheet metal against which one end edge of the card will bear when the card is fully inserted. In this way the cards will be uniformly inserted, and their end edges will be even when they are in the tray or drawer.

For the insertion of any card and its holder, all that is necessary is to skew the holder around obliquely to the tray until its ends are in position to pass downward into the tray and into the plane of the guides 2 previously mentioned. Then by straightening the holder around until it extends exactly at right angles to the length of the tray or drawer, the two cylindrical portions 3 of the holder will be brought into the guides 2, below the overhanging portions of these guides, as shown in Figs. 1 and 2, thus holding the card and its holder in place in the tray or drawer. When a number of cards and holders are in the tray, a follower of any suitable character can be placed against the last card holder, thereby to crowd the card holders tightly

together, so that the front edges 9 of the cards will be spaced apart a distance equal, or substantially equal, to the diameter of the tubular portions 3, when the cards are 5 lying flatwise upon each other, as shown in Fig. 1 of the drawings. For example, a spring follower 10, of the form shown and described, can be inserted in the grooves or guides 2, and can be released by squeezing 10 the middle portion of this follower to withdraw its ends from said guides when it is desired to remove or rearrange some of the cards, or to insert new cards.

Thus, if a new card is to be inserted at 15 some particular place between other cards, all that is necessary is to remove the follower and spread the cards and their holders apart, at the point where the new card is to be inserted, so that the holder of the new card 20 can be skewed when it is inserted, and when the holder of the new card is straightened around at right angles to the length of the tray or drawer, all of the card holders can then be pushed back together as shown and 25 described. Thus, it is not necessary to remove other cards when some particular card is removed, and it is not necessary to remove other cards when new cards are inserted.

The flat portion 4 of each holder is adapted 30 to compress the card, so that the card is frictionally held and cannot easily be pulled out. The cylindrical portions 3 of the holders are adapted to rotate in the guides 2, so that any card can be swung upward and over 35 backward without bending it, the end portions 3 forming pivots, so to speak, about which the cards and their holders can rotate without bending the cards.

It will be understood, of course, that the 40 form of the tray or drawer may be of any suitable character, and is merely shown conventionally to simplify illustration. Also the follower may be of any suitable character, but is merely shown in a simple form for 45 the sake of simplified illustration.

Of course, the cards and their holders may be used on any suitable support. Also, when used in a cabinet, it is obvious that the cabinet (not shown) may be of any suitable, known or approved character.

With the flat portion 4 of the card holder formed to tightly and frictionally grip the card, it would be difficult to insert the card directly in the slot, between the two flat 55 jaws of the holder, by motion at right angles to the holder. Therefore, the slot is preferably continued to the extreme ends of the holder, so that one corner portion of the card can be inserted in the end of the holder, and the card then pulled along until it reaches the stop 8 near the other end of the holder, as in this way the card can be inserted between flat jaws which very tightly grip the card. Thus the mere insertion of the card, 60 in the manner explained, is sufficient to hold

it in the holder, and after such insertion no denting or other distortion of the holder is necessary in order to retain the card therein.

With the stop 8 near one end of the card holder, it is apparent that the card must be 75 inserted at the other end of the holder. Furthermore, the holders are uniform, so that the stops 8 are in line, obviously, whereby each stop properly positions its allotted card on the tray or drawer or other support, 75 and whereby the side edges of the cards are all in line. Such alinement is also brought about, of course, by the uniform positioning of the card holders by the sides of the tray or drawer, whereby the latter co-operates 80 with the stops 8 to hold the series of cards with their side edges exactly even or in line.

Without disclaiming anything, and without prejudice to any novelty shown and described, what I claim as my invention is:

1. A visible card-index card-holder comprising a sheet-metal tube having a slot on one side thereof for the card, and having a flattened intermediate portion to frictionally grip the card, leaving two cylindrical 90 end portions projecting beyond the edges of the card, said slot extending to the outer ends of said end portions, so that the card may be inserted at one corner thereof in the end of the holder and moved along into 95 said flattened portion, with means forming a stop at one end of the flattened portion, to limit said insertion, preventing the card from being inserted through the cylindrical portion adjacent said stop, said stop 100 preventing the card from being pushed into the adjacent cylindrical portion, and positioning the card between the two cylindrical portions.

2. A structure as specified in claim 1, in 105 combination with a tray or drawer having guides to receive said cylindrical end portions, said stop positioning the card properly between the sides of the tray, these slotted end portions being adapted to serve 110 and act as trunnions in said guides, requiring skewing of the card and card holder obliquely to the length of the tray or drawer, for the insertion or removal of the card and card holder, and permitting the 115 adjusting of the card and card holder to a position at right angles to the length of the tray or drawer after the end portions of the card holder are thus brought into the plane of said guides.

3. A structure as specified in claim 1, in combination with a support having means to engage said cylindrical end portions, said stop properly positioning the card on the support, permitting the card holder to be 125 rotated about the axis of said cylindrical end portions, to change the position of the card without bending thereof.

4. A structure as specified in claim 1, in combination with a support for holding a 130

plurality of cards and their card holders of the character specified, with the cylindrical end portions of the card holders in a common plane and close together, so that when 5 the cards rest flatwise upon each other their free edges are spaced apart a distance substantially equal to the diameter of said cy-

lindrical end portions, the stops on the card holders properly positioning the cards with their side edges in line adjacent one side 10 of said support.

Specification signed this second day of March, 1925.

ALBERT G. WUEST.
